UNITED STATES PATENT OFFICE.

RICHARD M. COLGATE, OF WEST ORANGE, NEW JERSEY.

DESIGN FOR A BOX.

SPECIFICATION forming part of Design No. 30,412, dated March 28, 1899.

Application filed January 3, 1899. Serial No. 701,047. Term of patent 7 years.

To all whom it may concern:

Be it known that I, RICHARD M. COLGATE, a citizen of the United States, residing at West Orange, in the county of Essex and State of New Jersey, have invented and produced a new and original Design for a Box, of which the following is a specification, reference being had to the accompanying drawing, forming a part thereof, which represents a perspective view of a box embodying the features of my design.

A represents one end of a box of rectangular contour, B a side, and C the front of the box. Each end, side, and face of the box is ornamented by a decorative panel, the end

A of the box having the intaglio circular figures D in triangular arrangement.

The leading features of the design consists in a box of rectangular contour ornamented by decorative panels and having the intaglio circular figures at an end of the box, which circular intaglio figures are in triangular arrangement.

I claim—

The design for a box herein shown and described.

RICHARD M. COLGATE.
